MORRIS NOVER, OF JERSEY CITY, NEW JERSEY

HAND BAG

Application filed July 5, 1927. Serial No. 203,500.

The main object of the present invention is to provide an improved hand bag designed to effectually prevent loss of articles therefrom when it is closed and adapted to be freely opened and expanded to the maximum extent without injuriously straining or distorting any parts of its structure.

Other objects of the invention will appear hereinafter.

10 In the drawing:

Fig. 1 is a perspective view of the hand bag showing it opened and fully expanded;

Fig. 2 a front elevation of the opened bag;

Fig. 3 a vertical section upon a larger scale taken on the line 3—3 of Fig. 5 showing the bag closed;

Fig. 4 a fragmentary side view of the upper portion of the closed bag; and

Fig. 5 a horizontal section taken on the line 5—5 of Fig. 3.

The hand bag is of the envelope type and its structure includes a front wall 1 and a rear wall 2 foldably connected together along their lower edges as at 3. Connected to the 25 rear wall 2 along the upper edge 4 thereof is a freely foldable hinge portion 5 of elongated rectangular area. This hinge portion is formed to entirely cover the mouth of the pocket space between the walls 1 and 2 when the bag is closed. A flap 6 is foldably connected to the hinge portion along the forward edge 7 of the latter and is adapted to overlie the front wall 1 when the bag is closed. The flap and the front and rear walls are all rec- 35 tangular in form and of substantially the same size. Preferably they are formed in the usual manner by a single continuous sheet 8 of leather or other suitable material. This sheet extends from the upper edge of the front wall

40 1 clear to the outer free end of the flap and forms an outer facing for the walls 1 and 2, the hinge portion 5 and the flap 6. Extending over the area of the inner side of said sheet is a lining 9 of any suitable material, the 45 edges of the sheet being folded inwardly and stitched to the lining in the usual manner.

Interposed between the facing sheet 8 and the lining 9 are relatively thick filling sheets 10 of any suitable material. The sheets 10 ex- 50 tend respectively over the areas of the front

and rear walls 1 and 2 and the flap 6. The filler sheet of the rear wall 2 terminates at the upper edge 4 of the rear wall and the sheet within the flap 6 terminates at the forward edge of the hinge portion 5. This filling 55 material gives a desired body and stiffness to the front and rear walls and to the flap. It is omitted from the area of the hinge portion between the lines 4 and 7 to render said portion more flexible than the walls and the flap. 60 If desired one or more thin sheets of suitable material 11 may also be included between the facing and lining sheets and this material may be extended over the area of the hinge portion also to give the latter a de- 65 sired body or thickness without materially reducing its flexibility.

The opposite sides of the space between the front and rear walls of the bag are defined by gussets 12 each formed with a facing 13 and 70 a lining 14 similar to those of the remainder of the bag. The forward edges of the gussets extend along the entire length of the side edges of the front wall and are stitched thereto. The rear edges of the gussets extend 75 along the entire length of the side edges of the rear wall 2 and also along the length of the side edges of the hinge portion 5 and are stitched to both. The upper ends of said rear edges of the gussets terminate substantially at 80 the forward edge line 7 of the hinge portion. The gussets are so formed that when the bag is opened and fully expanded, as shown in Fig. 1, their upper edges 15 will extend in substantially straight lines from the 85 upper edge of the wall 1 to the forward edge line 7 of the hinge portion 5.

Within the bag is a partition 16 which extends entirely across the width of the interior and is secured at its ends to the rear wall 2. 90 This partition defines a pocket at the inner face of said wall. Secured to the forward face of the partition 16 is a purse 17 the width of which is materially less than that of the interior space of the bag. A smaller pocket is 95 formed upon the inner face of the front wall 1 by a sheet of material 18 stitched to said wall. Upon the outer face of the rear wall 2 is secured a diagonally arranged hand-strap 19 for carrying the bag. Companion snap 100

fastenings 20 are provided upon the flap adjacent the free end thereof and upon the front wall 1 to hold the flap closed.

Each of the gussets 12 is creased to fold on a plurality of lines. In this manner the folded thickness of the gussets, when the bag is closed, is rendered substantially equal to the thickness of the purse 17. The gusset folds extend inwardly to points closely adjacent the sides of the purse and fill the marginal spaces between the purse and the side edges of the walls as indicated in Fig. 5. When the bag is closed the rearmost fold of each gusset is disposed against the partition 16 and against the hinge portion 5 and the upper extended portion of the gusset is folded with the hinge portion to extend entirely across the mouth of the bag at the marginal ends thereof as shown in Figs. 3 and 4. This folding of the extended ends of the gussets effectually seals the rearinost pocket of the bag. The said ends also extend across the remaining folds of the gussets at the edges of the purse and co-operate with said folds to prevent the contents of the forward pockets from escaping between the gussets and the hinge portion.

In opening a hand bag of this type it is customary and natural to grasp the upper end of the front wall and the free end of the flap and pull them in opposite directions to fully expand the bag, as shown in Fig. 1. In the present bag the design of the gussets and their manner of attachment permits the bag to be expanded in this manner freely, fully and safely. The raising of the flap to the position shown in Fig. 2 swings back the hinge portion 5 and the upper ends of the gussets to uncover the mouth of the bag. When the flap and the front wall of the bag are pulled in opposite directions to expand the bag the hinge portion 5, owing to the attachment of the gussets to it, swings back in the same plane with the rear wall 2 as though both were a single leaf. A straight pull is transmitted through the gussets, from the upper edge of the front wall 1 to the forward or upper edge 7 of the hinge portion 5. This straight pull completely straightens out the gussets so that they offer no obstruction at the mouth of the bag. The termination of the gussets at the fold line 7 leaves the flap free to swing straight back at this line in the direction of said pull, to a position substantially within the plane of the upper edges of the gusset, without straining or distorting the gussets or tearing open their stitching.

What I claim is:

60 In a hand bag of wallet form including a pair of substantially co-extensive and relatively stiff front and rear leaves foldably connected together along their lower edges and a relatively stiff flap to fold over the front leaf, a freely flexible hinge and closure

portion foldably connecting together the rear leaf and the flap clear across the bag; and a pair of inwardly folding and downwardly tapering side gussets having substantially straight upper edges, straight front edges stitched to the front leaf, and straight rear edges longer than the front edges extending along substantially the side length of the rear leaf and hinge portion combined, stitched to both and terminating, with their stitching, at points closely adjacent to the flap, whereby the upper rear corners of the gussets will fold inwardly against the hinge portion and forwardly therewith to closed position, and when the bag is spread open the hinge portion will lie in the plane of the rear leaf and the flap may be swung rearwardly and downwardly to any degree without straining the gussets or their stitching.
